UNITED STATES PATENT OFFICE.

FRANK M. BURROWES, OF PORTLAND, MAINE.

FOLDING TABLE.

1,215,479.

Specification of Letters Patent. Patented Feb. 13, 1917.

Application filed March 12, 1913. Serial No. 753,652.

To all whom it may concern:

Be it known that I, FRANK M. BURROWES, a citizen of the United States, residing at Portland, in the county of Cumberland and State of Maine, have invented certain new and useful Improvements in Folding Tables, of which the following is a specification.

This invention relates to improvements in folding tables, that is, tables in which the legs, when not in use, are adapted to be folded up against the bottom of the table. It is adapted to be used in connection with tables having any peripheral outline, and for the purpose of illustration, I have shown it in connection with a table having a circular top. Its structure is such, that, when desired, the top of the table may be of comparatively small size, the legs being adapted to extend beyond the center of the table.

In the drawing herewith accompanying and making a part of this application, Figure 1 is a bottom plan view; Fig. 2 is a detail sectional view, showing the mechanism 25 for and method of holding the legs in unfolded position; Fig. 3 is a detail sectional view showing the relative position of the legs, one above the other, and the method of holding the legs yieldingly locked in folded 30 position; Fig. 4 is a plan view of the blank for the spring leg holder; and Fig. 5 is a detail of the brace box and a coil spring for preventing accidental folding of the leg.

Same reference characters indicate like 35 parts in the several figures.

In said drawing A represents the top of a table and B a downwardly extending peripheral flange or skirt. The width of this flange is preferably such that when the legs 40 are folded across each other, as shown in Fig. 1, the outside of the legs will be substantially in the plane of the lower edge of said flange. Secured to the flange at suitable points are angle irons C, and to the bottom 45 side of the table a plurality of rigid bars D, positioned at suitable distances apart. These bars extend from the inside of the flange to a suitable point spaced apart from the center of the table and have their inner 50 ends beveled outwardly, as seen at E. Between angle irons C and bars D, the legs F are pivotally secured, each being mounted on a pivot pin G. Secured to the side of each arm D is a plate H provided with a slot 55 adapted to receive and guide the off-set end J of a leg holding spring brace K. Each

slot has a curved portion L being substantially in the arc of a circle of which the fixed end of the brace bar is a center and the remaining portion offset M in a different arc, the purpose of which will be hereinafter described.

One end of plate H is spaced apart from the side of bar D by means of a spacing block N a distance sufficient to permit the 60 offset end of the brace to move freely and to enable it to project far enough beyond the plate to prevent it from being accidentally displaced. It is also spaced apart from the leg by means of a spacing block O a sufficient distance to permit free movement of 65 said brace. Secured to the under side of the table near the center is a plate P provided with a downwardly extending post Q. Upon this post is mounted a spring R, having a 70 plurality of leaves S which are bent downwardly substantially as seen in Fig. 3, said leaves being positioned so that the legs, when folded, press between the leaves and the ends 75 of the bars and are held yieldingly thereby. 80

It will be noted that the legs which fold first against the bottom of the table and the controlling slotted plate are positioned nearer the bottom of the table than those which fold outside. This is due to the fact 85 that the legs fold, one over the other, and it will be evident that this would not be necessary if the legs extended only to the center of the table. The legs are held yieldingly 90 in unfolded position either by an inherently elastic spring bar or by means of a coil spring T, as seen in Fig. 5.

The operation of my improved device is as follows:

Starting with the legs in operative position, the legs which fold next to the table are first released by manually moving the free end of each of the brace bars K in its slot outwardly toward the edge of the table until the offset end J reaches the offset curve. 95 The legs may now be moved into folded position, the offset in the brace bar moving into the offset curve. When completely folded, the legs are yieldingly engaged and held between the leaves of the spring at the center 100 and the ends of the fixed bars D. The other legs are then folded in a similar manner. To reset the table, it is only necessary to move the free ends of the legs outwardly, in 105 which position they are held yieldingly by a spring tension inherent in the brace bar or in a spring specially provided therefor.

Having thus described my invention and its use, I claim:

1. In a table, a table top provided with legs pivotally attached to the bottom thereof, 5 plates secured to the underside of the table and provided with slots having unequally curved sections and spring braces secured to the legs and terminating in offsets adapted to travel in said curved slots, whereby the 10 braces are caused to travel automatically from the outer to the inner portions of the slots as the legs are unfolded and to be held yieldingly under tension in unfolded position.
- 15 2. In a table, a top provided with legs pivotally attached thereto, a central post secured to said table, springs mounted upon said post, radial bars extending outwardly from a point near said post, whereby said 20 legs when folded are engaged and yieldingly held between said bars and springs.
3. In a table, a table top provided with legs pivotally attached to the bottom thereof, plates secured to the bottom of the table

top provided with slots having upwardly extending curved offsets, spring braces having one end secured to the legs and the other terminating in an offset adapted to travel in said slot and springs adapted automatically to cause said offsets to travel to the inner 30 ends of said slots as the legs are unfolded.

4. In a folding table, a top provided with a downwardly extending peripheral flange, four legs longer than the semi-diameter of the table pivotally attached to the bottom of the table at points diagonally opposite each other and adapted to fold against the bottom of the table outside the center thereof, a post located at the center of the table and provided with four springs, said springs being adapted to yieldingly engage the legs intermediate their ends, and fixed bars on the under side of the table adapted to engage the opposite sides of the legs.

FRANK M. BURROWES.
